UNITED STATES PATENT OFFICE.

WILLIAM DAVEY ODDY, OF LEEDS, ENGLAND.

PROPELLER.

1,362,032.

Specification of Letters Patent. Patented Dec. 14, 1920.

Application filed June 10, 1919. Serial No. 303,174.

To all whom it may concern:

Be it known that I, WILLIAM DAVEY ODDY, a subject of the King of the United Kingdom of Great Britain and Ireland, residing 5 at Leeds, England, have invented certain new and useful Improvements in Propellers, of which the following is a specification.

The present invention relates to propellers and consists in the provision of improved 10 means for mounting wooden blades on the propeller shaft. Further, by the methods hereinafter described two or more propeller blades separately manufactured may be fastened together to form a complete propeller.

15 The improved means according to the present invention consists in the provision of a wedge shaped member, which engages a correspondingly shaped slot in the inner end of the blade, as an intermediate connection

20 between a wooden propeller blade and a member adapted to be mounted in any suitable manner on the propeller boss or shaft.

To this end the blade is suitably provided with an inner end portion or shank 25 which is gripped between said wedge shaped member, which engages in a correspondingly shaped slot in the shank, and a sleeve or strap adapted to fit tightly around said shank.

30 The wedge is preferably made of steel and may be notched or serrated and fits accurately into the slot in the shank with its wider end outward.

In a preferred form of construction, as is 35 hereinafter described, the wedges for opposite blades are made integral. In this case the sleeves also for opposite blades are preferably made integral, and can therefore be secured directly to the propeller shaft without 40 the use of the usual metal boss. Said sleeves which are preferably of steel may be made in halves which can be clamped together by bolts or like means.

The shank is preferably cylindrical. The 45 slot in the shank is shaped correspondingly to the wedge, the outer end being the wider, and the wedge is inserted laterally into it. Said slot may be notched or serrated to correspond with any notches or serrations of 50 the wedge, or the wedge may be driven into the slot so that the serrations cut into the wood.

The nature of the construction whereby 55 the blades are secured to the propeller shaft is, in a preferred form, as follows—

Two propeller blades with their slotted

shanks are connected by a double wedge, integral for the two blades, which is inserted laterally into the slots. A sleeve which is in halves is then placed around the two 60 shanks and clamped together by bolts or like means, thereby gripping the blades firmly between the sleeve and the wedge, and forming a rigid connection. In this case, when the sleeves for opposite blades are made integral, as are also the wedges, said sleeve can be secured directly to the propeller shaft without the use of the usual metal boss. Any suitable form of mounting may be employed, a convenient one being that comprising a tapered propeller shaft engaging in correspondingly tapered holes in the bosses of the sleeve, the shaft being provided with a tightening nut and being preferably keyed to the bosses. 75

It will be obvious that the sleeves might be cruciform or star form, as well as the member carrying the aforesaid wedges, whereby more than two blades could very simply be secured to the same propeller 80 shaft.

The accompanying drawings illustrate by way of example one embodiment of my invention. In these drawings—

Figure 1 is a view of the blade mounting 85 looked at in the direction of the axis of the shaft.

Fig. 2 is a view of same at right angles to said axis.

Fig. 3 is a section on the line III—III in 90 Fig. 2. Referring to the drawings, the blades, which may be of similar form to the ordinary propeller blades between the points *n*, *n* and the tips, are of cylindrical form from the points *n*, *n* to the inner ends 95 *o*, *o*.

A double wedge *p*, *q*, preferably of steel, is fitted laterally into correspondingly shaped slots in the shanks of the blades. The wedge *p*, *q* may be notched or serrated 100 and, if desired, it may be forced or driven into the slots so that the serrations cut into the wood. The sleeve *r*, *r*, preferably of steel, is made in halves and joined together by bolts *s*, *s* which when screwed up pull the 105 halves of the sleeve tight upon the blade shanks.

Thus the blades, wedge and sleeve are all held tightly together, and form a rigid connection, which may be enhanced by the 110 action of the nut *k* hereinbelow described.

The sleeve is mounted directly upon the

propeller shaft and the details of the mounting will depend on the form of the shaft. The arrangement shown, wherein the nut *k* 5 pulls a tapered propeller shaft *h* into corresponding tapered holes in the bosses *l*, *l* (which are integral with the sleeve *r*, *r*), the shaft being preferably keyed to the bosses by a key *m* (Fig. 3) which engages with keyways in the shaft and bosses and the 10 wedge also being bored with a hole to admit the shaft, is typical of an arrangement which might be adopted on a shaft of normal design. In this case the tapered portion of the shaft may co-act with the inner end 15 of the shank of the blade so that on tightening the nut *k* the blade is forced outward and therefore still more firmly gripped by the wedge.

It will be understood that by a wedge or 20 wedge-shaped member is meant a member that is of greater width or thickness at one end (*i. e.* the outer end) than at the other end, whether gradually tapered or abruptly enlarged.

25 What I claim is;

1. The combination of a propeller shaft, a plurality of propeller blades having shanks provided with wedge-shaped slots, outwardly diverging wedge-shaped members 30 engaging in said slots, sleeves surrounding said shanks and provided with holes in which the propeller shaft engages and means on said shaft for holding said sleeves on the latter.

35 2. The combination as claimed in claim 1,

wherein two or more of the wedge-shaped members are integral.

3. The combination as claimed in claim 1, wherein the propeller shaft is provided with a tapered end and the sleeves with correspondingly tapered holes. 40

4. The combination as claimed in claim 3, in which the end of the propeller shaft is screw-threaded and in which the means for holding the sleeves on the shaft consist of a 45 tightening nut on said screw-threaded shaft.

5. The combination as claimed in claim 3, in which the shanks of the blades abut against the tapered end of the propeller shaft. 50

6. The combination as claimed in claim 2, in which two or more integral wedge-shaped members are provided with a hole through which the propeller shaft passes.

7. The combination as claimed in claim 1, 55 in which the sleeves consist of halves provided with interconnecting devices.

8. The combination as claimed in claim 1, in which the wedge-shaped members are serrated. 60

9. The combination as claimed in claim 1, in which the propeller shaft and sleeves are provided with keyways in which a key engages.

In testimony whereof, I affix my signature in the presence of two witnesses.

WILLIAM DAVEY ODDY.
